UNITED STATES PATENT OFFICE.

GEORGE E. DOW, OF ROCHESTER, NEW YORK.

STEAM-ENGINE.

SPECIFICATION forming part of Letters Patent No. 359,435, dated March 1, 1887.

Application filed December 16, 1885. Serial No. 185,661. (No model.)

To all whom it may concern:

Be it known that I, GEORGE E. DOW, a citizen of the United States, residing at Rochester, in the county of Monroe and State of New York, have invented a new and useful Steam-Engine, of which the following is a specification.

My invention has reference to an engine in which two pistons, attached rigidly to opposite ends of a connecting-rod, are arranged to reciprocate in cylinders subject to the pressure of steam against their outer faces; and it consists in an improved construction of a tubular reciprocating valve adapted to be rotated on its axis to reverse the motion of the engine, and in various details in the construction and arrangement of the several parts whereby a durable, economical, and compact engine is secured.

Referring to the accompanying drawings, Figure 1 represents a horizontal longitudinal central section through my engine. Fig. 2 is a side elevation, partially in section, of the main valve and the steam-chest in which it is mounted. Fig. 3 is a side elevation of the engine.

Referring to the drawings, in constructing my engine I first provide a body consisting of two cylinders, A, closed at their outer ends and attached at their inner ends to an intermediate body or chamber, B, into which they open, as shown. I prefer to form this entire body in one piece of cast metal, as shown in the drawings, but it is manifest that the cylinders may be constructed separately and bolted or otherwise secured to opposite ends of the intermediate body or chamber. In each of the cylinders I mount a piston, C, and attach these two pistons rigidly to opposite ends of the connecting-rod D. Through a stuffing-box at one side of the chamber B, I insert the main engine-shaft G, provided at its inner end, within the chamber B, with a crank or crank-wheel, F, which is connected by a pitman, E, to one end of the rod D, as plainly shown in Fig. 1, this arrangement causing the reciprocating movements of the pistons to effect the rotation of the crank and shaft.

As a means of permitting the escape of the exhaust-steam at the end of the stroke, longitudinal ports or grooves t are formed at the inner ends of the cylinders, so that as each piston completes its inward stroke it will pass

over and uncover the inner ends of the grooves, whereupon the steam will escape from the 55 cylinder past the periphery of the pistons through the grooves into the chamber B.

To the side or top of the body I secure a valve-chest, H, of cylindrical form in cross-section. This chest extends the entire length 60 of the engine and communicates near its opposite ends, by ports a a', with the outer ends of the respective cylinders. At one end the chest H is connected to the steam-supply pipe J, from which the live steam passes into the 65 chest H, and thence by the valve, to be presently described, through the ports a a' into the two cylinders alternately, thus driving the pistons to and fro.

I represents the main valve, constructed of 70 a tubular form and mounted within the valve-chest H in such manner that it may reciprocate and also revolve, for purposes of reversal, upon its own axis. Ports b and b' are formed through this valve on one side in such position that they register alternately with the ports a a', in order to permit the live steam to pass into the cylinders. On the opposite side the valve is provided with similar ports, c and c', which may be brought into action by 80 giving the valve a half-revolution about its longitudinal axis. These second ports are in such position with reference to the ports b and b' that when brought into action they will reverse the course of the steam through the ports 85 a and a', and thus reverse the motion of the engine.

At each end the valve is provided in its periphery with exhaust-ports, each consisting of a longitudinal groove, g, having lateral 90 branches h and h', as plainly shown in Fig. 2. These ports are for the purpose of permitting the escape of such steam as may fail to escape through the ports t. At its two ends the valve is fitted closely within the surrounding steam-chest, but at about the middle portion of the valve there is an annular space, k, between the periphery of the valve and the interior of the chest, formed in the present instance by enlarging the internal opening of the chest. This 95 annular space communicates on one side through a port, m, with the central chamber, B, of the body, and also communicates with the exhaust-pipe n, leading from the engine.

As the valve is moved to and fro longitudinally the exhaust-ports at the opposite ends

are brought into action alternately. As each port is called into action its longitudinal portion *g* communicates with the steam-space *k*, and at the same time one of its lateral branches, 5 *h* or *h'*, (according to the direction in which the engine is running,) communicates with the port *a* or *a'*, leading into the adjacent cylinder, as shown in the right hand of Fig. 2, so that the steam escapes through the cylinder-port 10 into the lateral branch of the exhaust-port, and thence through the longitudinal portion of said port into space *k*, and finally through the port *m'* into the crank-chamber *B*.

To effect the longitudinal motion of the 15 valve I extend a rod or spindle, *o*, from its end through a stuffing-box to the exterior and connectsaid spindle by a swiveling connection, *J'*, to a pitman, *K'*, actuated by an eccentric, *L*, on the main shaft.

20 To secure the reversal of the engine I make the valve rod or spindle of angular form in cross-section and pass it through a corresponding guide, *p*, provided with a hand-lever and mounted in a stationary standard or other supporting port, *q*. By turning this handle I am not only enabled to reverse the motion of the engine, but to control the amount of live steam entering the cylinder.

The chamber or body *B*, through which the 30 steam escapes and in which the crank and its connections are tightly inclosed, is provided at its top with a large flanged opening, covered by a removable plate, *P*, the removal of which will afford access to all the internal parts.

35 The construction of my engine is such that if a lubricator be attached to the steam-supply pipe the oil entering said pipe will, in regular course, pass to the bearing-surfaces of the valve and the pistons, and will, in its course, 40 thoroughly lubricate the crank-connections.

To regulate the quantity of steam used by the engine a governor of any approved construction may be connected with the valve-spindle to effect its rolling or rotating motion.

45 It is to be noted that in my engine the valve is of exceeding simplicity and that the steam-pressure is so applied that the valve will be operated with slight friction.

I am aware that two pistons have been attached to opposite ends of a connecting-rod and arranged to work in separate cylinders, and also that tubular valves have been constructed in various forms; but I believe myself to be the first to construct and arrange the 55 ports in the manner shown in the drawings and recited in the following claims.

I believe myself the first to provide a cylinder with two distinct ports for exhausting the steam from one and the same side of the piston, one port controlled by the piston and the other by an automatic valve, and it is manifest that as regards this combination the valve may be of any ordinary construction.

Having thus described my invention, what I 65 claim is—

1. In a reversible steam-engine, the two cyl-

inders and their connected pistons, in combination with the cylindrical valve-chest closed at one end and provided with a steam-admission pipe at the opposite end, the port leading from said chest to the chamber between the pistons, and the tubular valve having a central opening from one end to the other, said valve provided at each end with the two steam-inlet ports extending therethrough and with an exhaust-slot having lateral branches, said valve having its ends fitted closely within the encircling-chest.

2. The tubular valve having the live-steam passage therethrough from end to end, the live-steam ports opening outward therethrough, and the exhaust ports or grooves in its outer surface, in combination with mechanism, substantially as described, for imparting a longitudinal motion thereto, the spindle *o*, fixed to the valve and projecting externally, and the rotary guide *P*, through which the spindle passes, provided with a hand-lever, whereby the attendant may adjust the levers without stopping its motion.

3. In a reversible steam-engine, two cylinders closed at their outer ends and provided with steam-ports, an intermediate closed chamber communicating directly with the inner ends of both cylinders, two pistons mounted in the respective cylinders and connected by an intermediate rod, a cylindrical valve-chest communicating midway of its length by the port *m* with said chamber, and the rotary reciprocating valve *J*, having its two ends fitted closely within the surrounding chest and provided with induction and eduction ports, as described, and its middle surrounded by a chamber, *h*, communicating directly with the chamber between the cylinders.

4. The cylindrical valve-chest with a steam-admission opening at one end and two ports, *a* *a'*, at its side; in combination with the tubular valve fitted closely at its ends within the chest and surrounded at the middle by an exhaust-steam space, said valve provided at each end with inlet-ports therethrough and with exhaust-ports in its outer surface, the exhaust-ports adapted to connect the ports *a* *a'* with the exhaust-steam space.

5. In a steam-engine, the two cylinders closed at their outer ends and opening at their inner ends directly into the intermediate crank-chamber, each cylinder provided at the outer end with a steam-port, *a*, and at the inner end with a grooved port, *t*, opening directly to the crank-chamber, in combination with the connected pistons arranged to uncover the respective ports *t* and the valve, substantially as described, delivering steam alternately into and out of the cylinders through the outer ports, *a*.
